(57) **CLAIM**

The ornamental design for a combined blow and vacuum cleaner set, as shown and described.

DESCRIPTION

FIG. 1 is a right side perspective view of a combined blow and vacuum cleaner set, showing my new design.

FIG. 2 is a rear and bottom perspective view thereof.

FIG. 3 is a rear and bottom perspective view of a combined blow and vacuum cleaner set, showing my new design with the first head attached.

FIG. 4 is a front and top perspective view thereof.

FIG. 5 is a bottom view thereof.

FIG. 6 is a top view thereof.

FIG. 7 is a left side view thereof.

FIG. 8 is a right side view thereof.

FIG. 9 is a front view thereof.

FIG. 10 is a rear view thereof.

FIG. 11 is an enlarged view taken from line 11 in FIG. 4.

FIG. 12 is an enlarged view taken from line 12 in FIG. 5.

FIG. 13 is a rear and bottom perspective view of a combined blow and vacuum cleaner set with the second head attached.

FIG. 14 is a front and bottom perspective view thereof.

FIG. 15 is a rear and bottom perspective view of a combined blow and vacuum cleaner set with the third head attached.

FIG. 16 is a front perspective view thereof.

FIG. 17 is a rear and bottom perspective view of a combined blow and vacuum cleaner set with the fourth head attached.

FIG. 18 is a front and top perspective view thereof.

FIG. 19 is a rear and bottom perspective view of a combined blow and vacuum cleaner set with the fifth head attached.

FIG. 20 is a front and top perspective view thereof.

FIG. 21 is an enlarged view taken from line 21 in FIG. 19.

FIG. 22 is a rear and bottom perspective view of a combined blow and vacuum cleaner set with the sixth head attached; and,

FIG. 23 is a front and bottom perspective view thereof.

The broken lines represent portions of the combined blow and vacuum cleaner set that form no part of the claimed design. The broken lines in the drawings depict enlarged views and form no part of the claimed design.
